United States Patent Office

Des. 229,682

Patented Dec. 25, 1973

229,682

HOUSE

Mark L. Hildebrand, Altadena, Calif.
(157 Bowers Hill Road, Oxford, Conn. 06483)

Filed Sept. 1, 1971, Ser. No. 177,204

Term of patent 14 years

Int. Cl. D25—03

U.S. Cl. D13—1 A

FIGS. 1 and 2 are, respectively, the front and back perspective views of a house.

FIGS. 3 and 4 are, respectively, the side and top views of a house of FIGS. 1 and 2.

FIG. 5 is a cross-sectional view through 5—5 of FIG. 4.

FIG. 6 is a cross-sectional view through 6—6 of FIG. 5.

FIGS. 7 and 8 are, respectively cross-sectional views through 7—7 and 8—8 of FIG. 6.

I claim:

The ornamental design for a house, substantially as shown.
